[57] CLAIM

The ornamental design for a wet and dry vacuum cleaner, as shown and described.

DESCRIPTION

FIG. 1 is a perspective view taken from the top, front and right side of a wet and dry vacuum cleaner showing my new design;

FIG. 2 is a left side elevational view thereof;

FIG. 3 is a front elevational view thereof; and

FIG. 4 is a bottom plan view thereof.

The fragmentary broken line representation of a vacuum hose in FIG. 1 is for purposes of illustration only.
